UNITED STATES PATENT OFFICE

2,535,802

LAMP VAPORIZER

Philip Libson, Brooklyn, N. Y., assignor to
 Helena Rubinstein, Inc., New York, N. Y., a
 corporation of New York

Application May 22, 1948, Serial No. 28,673.

7 Claims. (Cl. 21—120)

1

My invention relates to an improved vaporizer of the type which is applicable to an electric light bulb from which it obtains the necessary degree of heat required to volatilize the substance to be evaporated. The invention has particular application as an evaporator of deodorants and especially perfumes and is constructed to accommodate dry volatile solid compounds.

The invention has for its principal object to provide a detachable holder adapted to yieldably grip a lamp bulb about its hemispherical portion and to receive and hold a cartridge containing the perfumed compound into close contact with the bulb so as to utilize the heat generated by the latter to vaporize the compound and allow it to escape to the atmosphere.

A further object of the present invention is to provide a suitable container for the volatile compound which may be readily and easily inserted and removed from the holder and which will permit the escape of fumes therefrom when subjected to the necessary degree of heat.

A still further object of my invention is to provide the vaporizer with a novel gripping arrangement which attaches itself to an electric light bulb where the greatest heat is generated and at any practical angle with respect thereto, i. e. if the bulb is disposed in dependent position instead of upright, the holder may be successfully applied and the container for the compound will still be in proximity to the bulb and may utilize the heat therefrom to evaporate the compound and allow the perfumed fumes to escape.

The various objects of my invention are accomplished by means of the vaporizer and compound container hereinafter described in the specification, set forth in the appended claims and illustratively exemplified in the accompanying drawings in which:

Fig. 1 is a side elevational view of one embodiment of my invention as applied to an electric light bulb and illustrating the compound container in section;

Fig. 2 is a top plan of the same;

Fig. 3 is a side elevational view of modified embodiment of the vaporizer; and

Fig. 4 is a top plan view of the same.

Referring to the drawings and particularly Figs. 1 and 2, 10 denotes an electric light bulb of the usual construction and contour having a hemispherical outer end portion 11. The holder for the material to be evaporated comprises a substantially rectangularly shaped frame 12 composed of a flat strip of metal, preferably of a springy type, in which the longer sides form the

5 top and bottom and in which the shorter sides forming the ends are slightly flared outwardly from each other. One of the longer sides carries on its outer surface and at the center thereof a plurality of arc shaped yieldable wire fingers 13 which are arranged to be sprung over the hemispherical end 11 of the bulb 10 to engage the end and firmly hold the vaporizer to the bulb. The opposite long side of the frame 12 carries a ball or grip 14 on its outer face for the purpose of providing means for handling the vaporizer especially when heated, and for applying the device to the bulb and removing it therefrom.

15 The cartridge or container 15 for the volatile solid material comprises a metal shell of preferably two pieces 16 of disc shape having upstanding peripheral flanges 17 which fit together to complete the container. The disc shaped pieces 16 are provided with perforations 18 through which the fumes of cake 19 of volatile material may escape. The container 15 is of a diameter to fit snugly between the end walls of the frame 12, while its height is accommodated between the two longer walls. Frame 12 thus forms in effect 20 a resilient loop element which embraces the container of cartridge 15. The dimensions of this resilient loop element (frame) and the springiness of the material thereof provide a sliding fit between container and frame to hold the 25 former firmly in the latter.

20 Referring now to the alternate form of the invention illustrated in Figs. 3 and 4, the gripping elements embracing the bulb 10 comprise wire spring loops 21 which are attached to a frame 22 and depend therefrom in spaced parallel relation until they are spread apart to spring over and about the hemispherical end portion 11 of the bulb 10 to hold the vaporizer thereon. The inner wall 23 of the frame 22 is curved 25 to conform approximately to the contour of the bulb and is provided with an opening 24 whereby the bulb is exposed directly to the interior of the frame 22 and is brought into close contact with the container 15 when placed in the frame. The outer long side of the frame 22 is a narrow strip of metal so as to cover only a minimum surface of the container 15 and afford a greater exposure 30 of the perforated disc sides of the latter.

35 In operation, a container 15 is selected which contains the desired perfume or deodorants, and it is inserted into the frame 10 or 22 and the vaporizer is attached to the bulb 10 by merely allowing the fingers 13 or loops 21 to be pressed 40 against the bulb until they spring into gripping position. The container 15, as seen from the 45

drawings, will be very close to the bulb or in contact therewith so as to cause a maximum of heat from the bulb to be transferred directly to the container and its contents, which will almost immediately begin to evaporate and perfume vapors to be emitted through the perforations 18. One of the desirable features of utilizing solid material as a carrier for the material to be vaporized is that the vaporizer may be placed in any desirable position without fear of the contents of the container falling or spilling out of the latter.

The vaporizer, as constructed in Figure 1, permits the user to stand it erect on the four prongs 13, after it is removed from the lamp. This permits the heated container to be kept remote from the surface of the table or other object on which it is placed while cooling, thus eliminating any possible damage from the heat.

Having now described my invention and the manner in which the same is utilized and operated, what I claim and desire to secure by Letters Patent is:

1. In a vaporizer applicable to an electric light bulb, the combination of a frame having means to embrace the hemispherical end portion of the bulb, and a container for a volatile compound removably carried by the interior of said frame in heat exchange relation with the bulb, said frame being composed of a continuous band having the portion held against the bulb provided with an opening to allow the said container to contact the bulb.

2. A vaporizer comprising a separate and independent cartridge adapted to receive a volatile substance, a resilient loop element, said cartridge being detachably received and supported within said loop element, a support having a portion adapted for direct contact and engagement with the globe of an incandescent light bulb, said loop element being secured to said support and holding said cartridge in proximity to said globe engaging portion of said support to establish heat exchange relation between said cartridge and said bulb when the latter is engaged by said support. 45

3. A vaporizer, as claimed in claim 2, in which the cartridge comprises a hollow disc shaped element to contain a solid volatile substance, the opposite walls of the cartridge being perforated to permit escape of the vapors from the substance to atmosphere when the heat from the bulb has caused volatilization of the substance.

4. A vaporizer, as claimed in claim 2, including a holding element attached to the loop element to facilitate application and removal of the vaporizer from the bulb without fear of being burned by contact with the highly heated parts of the vaporizer.

5. A vaporizer, as claimed in claim 2, in which said support comprises spring wire elements adapted to be forced over and about the hemispherical end portion of the bulb.

6. A vaporizer, as claimed in claim 2, in which the support comprises a plurality of resilient wire fingers adapted to be spread when pushed over the hemispherical end portion of the bulb and closely embrace the latter to hold the cartridge to the same.

7. A vaporizer, as claimed in claim 1, in which said portion of the continuous band is curved to contact the hemispherical portion of the bulb said opening in said band being arranged in the said curved portion thereof to allow the bulb and container to contact in direct heat exchange relation.

PHILIP LIBSON.
